(57) CLAIM

The ornamental design for a cooking utensil handle, as shown and described.

DESCRIPTION

FIG. 1 is a top, side and front perspective view of a cooking utensil handle showing the new design;

FIG. 2 is a left side elevation view thereof;

FIG. 3 is a right side elevation view thereof;

FIG. 4 is a rear side elevation view thereof;

FIG. 5 is a front side elevation view thereof;

FIG. 6 is a top plan view thereof; and,

FIG. 7 is a bottom plan view thereof.

The broken line showing environmental structure is for illustrative purposes only and forms no part of the claimed design.
